(57) **CLAIM**

The ornamental design for a disposable integrated endoscope, as shown and described.

DESCRIPTION

FIG. 1 is a perspective view of a disposable integrated endoscope showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The disposable integrated endoscope has an elongated rod which is shown by a symbolic break in FIGS. 1 and 4-7. The appearance of any portion of the article between the break lines forms no part of the claimed design.

The dash-dot lines shown in FIGS. 2, 4, 5, and 7 depict boundaries of the disposable integrated endoscope that form no part of the claimed design. The dashed broken lines shown in FIG. 2 illustrate portions of the disposable integrated endoscope that form no part of the claimed design.
